UNITED STATES PATENT OFFICE.

HARRY A. McLAUGHLIN, OF JACKSONVILLE, FLORIDA.

ATTACHMENT FOR RULERS.

1,109,444.

Specification of Letters Patent.

Patented Sept. 1, 1914.

Application filed August 26, 1913. Serial No. 786,789.

To all whom it may concern:

Be it known that I, HARRY A. McLAUGHLIN, a citizen of the United States, residing at Jacksonville, in the county of Duval and State of Florida, have invented certain new and useful Improvements in Attachments for Rulers; and I do hereby declare the following to be a full, clear, and exact description of the invention, such as will enable others skilled in the art to which it appertains to make and use the same.

My invention relates to an attachment for rulers, which affords means whereby the rulers may be used as a gage, square, miter, or bevel, as the case may be, and will in either instance be efficient in its operation.

An important object of my invention is to provide an attachment for rulers particularly, of the two-foot folding pocket ruler type, such as now in general use but it may obviously be attached to any style of ruler.

A further important object of my invention is to provide an attachment for rulers which may be readily and easily applied or detached, also adjusted to take the place of the gage, square, miter, and bevel, and one which consists of few parts, simple as to construction and cheap to manufacture.

The above and additional objects are accomplished by such means as are illustrated in the accompanying drawings, described in the following specification and then more particularly pointed out in the claim which is appended hereto and forms part of this application.

With reference to the drawings, wherein, I have illustrated the preferred embodiment of my invention as it is reduced to practice, and throughout the several views of which, similar reference numerals designate corresponding parts.

Figure 1 is a top plan view of my device in assembled operative position and shown attached to a ruler, Fig. 2 is a bottom plan view, Fig. 3 is a transverse vertical section taken on line 3-3 of Fig. 1 and illustrating the manner of securing the adjusting screw to the device, and Fig. 4 is a detail view of the co-operating portions of the slide and adjustable plate mounted thereon.

Referring now to the drawing forming a part of this specification and in which like numerals are employed to designate like parts throughout the same, the numeral 1 designates a slide, generally, which is preferably rectangular in shape and provided

with opposed right-angular sides 2 and 3 adapted to lie parallel with the side edges of a ruler A in spaced relation thereto.

As a means for clamping the slide upon the ruler, this invention employs a pair of spring metal gripping fingers 4 and 5 each of which are secured centrally of their ends to the right-angular sides 2 and 3, by means of a rivet 6 or other suitable fastening means. Each of the fingers 4 and 5 diverge from the point where they are secured and terminates beyond the ends of the sides 2 and 3 and base plate in outwardly turned terminals with relation to their divergent portions, as will be clearly seen with reference to Fig. 2. It is thus apparent that the slide may be fitted quickly upon the ruler and is held in gripping and sliding engagement thereupon.

The central portion of the base plate forming a part of the slide 1 is struck upwardly to provide an annular portion or boss 7 which is centrally apertured and has extended therethrough a vertical screw 8, the head 9 of which is held into engagement with the under face of the boss 7 by means of solder 10 which is applied to the head 9 within the depression provided by forming the boss 7. The solder 10 is applied so that it will be flush with the under surface of the base plate of the slide, to provide for the proper sliding action of the slide upon the ruler, and obviously holds the screw 8 securely against rotation upon the slide.

A rectangular plate 11 provided centrally with an upwardly struck annular portion 12 which provides a depression opening upon the under surface of the plate and adapted to engage the boss 7 formed on the base plate of the clamp 1. The portion 12 is centrally apertured to provide for the extension of the vertical screw 8 therethrough. The plate 11 is provided at one terminal with a transversely extending right-angular portion 13 which extends beyond the longitudinal edges of the plate 11 for a considerable difference and is formed integral therewith.

In an annulus about the vertical screw 8 and upon the upper surface of the base plate, is formed a plurality of graduations 14 which are formed by stamping depressions in the base plate. The graduations 14 extend from zero to 45 degrees. The plate 11 is reduced at one terminal to provide a pointed end 15 in which is stamped a de-

pression 16 for the purpose of affecting the engagement of the depression with the depressions forming the graduations 14.

As a means for clamping the plate 11 in any adjusted position in relation to the graduation 14, this invention employs a thumb screw 17 which is fitted upon the upper terminal of the vertical screw 8 and is adapted for engagement with the struck out portion 12 formed on a plate 11 to provide the desired action.

It is apparent that by adjusting the plate 11 carrying right-angular portion 13 that means are afforded whereby a ruler may be employed not only as a gage, but as a square, miter or bevel as well, and will in other instances give entire satisfaction owing to the manner in which it may be reversed and adjusted.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may

be resorted to, when required, without sacrificing any of the advantages of my invention, as defined in the appended claim.

Having thus described my invention, what is claimed is:

An attachment for rulers comprising a slide said slide consisting of a base plate, sides at right angles to said base plate formed integral with said base plate, a boss formed centrally on said base plate, a vertical screw mounted within said boss, a plate pivotally mounted upon said base plate, said plate having a transversely extending portion disposed in a plane at right angles to the plane of said plate, said last mentioned plate provided centrally with a depression adapted for engagement with said boss, said screw extended through said depression, and means for locking said plate in adjusted position including a thumb screw mounted on said vertical screw and adapted for engagement with said last named plate.

In testimony whereof I affix my signature in presence of two witnesses.

HARRY A. McLAUGHLIN.
